UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

POURING SPOUT FOR CONTAINERS.

Application filed October 22, 1920. Serial No. 418,693.

To all whom it may concern:

Be it known that I, JOHN M. HOTHERSALL, a citizen of the United States, residing in Brooklyn, in the county of Kings and State 5 of New York, have invented a new and useful Improvement in Pouring Spouts for Containers, of which the following is a specification.

This invention relates in general to containers and has more particular reference to a combined pouring spout and temporary closure to be used therewith, while the contents are being consumed.

A principal object of the invention is the provision of a convenient pouring spout, which is removable and which may be easily opened and closed after being attached.

A further important object of the invention is the provision of a spout adapted to be used in connection with filling hole closures of an improved general type, having a central depression and retaining wall.

A still further object of the invention is the provision of an improved combination 25 of a pouring spout and a temporary closure which may be easily positioned and removed by the user and which, therefore, may be used indefinitely, if desired, with cans of the same type.

Another highly important object of the invention is the provision of a spout inserted 30 within a receiving wall in the container and movable from a pouring position extending over the edge of the container to an inoperative position within said edge.

Other objects and advantages of the invention will be apparent as it is better understood from the following description when considered in connection with the accompanying drawing illustrating a preferred embodiment thereof.

Referring to the drawings,

Figure 1 is a top plan view of a container upon which the invention is employed;

Fig. 2 is a side elevation of the container;

Fig. 3 is a vertical section of the spout and closure taken on the line 3-3 in Fig. 1;

Fig. 4 is a vertical section of the spout;

Fig. 5 is a vertical section of the depressed closure; and

Fig. 6 is a vertical section of the filling hole neck.

The drawings disclose an exemplification of my invention and it will be noted that 55 they show a container body 11, which may

be of any preferred general construction, and which has in one end 12 a filling hole 13 having an upstanding neck 14. A closure 15 is attached by a three-wall joint, as indicated at 16, to said upstanding neck. Said 60 closure is centrally depressed and its wall 17 is slightly tapered, the bottom being larger than the top part thereof.

The spout 18 has an upstanding wall 19, which may be of any preferred design. In it 65 is an extended lip 21 over which the contents of the can are poured. A plug portion 22 of said spout is tapered to correspond with the tapering in the closure 15 and is thus adapted to be snapped into said closure 70 and to be frictionally held thereby. Of course, other suitable means of attachment might be employed, but frictional engagement is perhaps the simplest and an entirely satisfactory means. When so held, the spout 75 may be freely rotated, but can not be easily displaced.

An eccentric orifice 23 is provided in the base 24 of said spout. The closure 15 may be punctured by the user in such manner as to 80 provide an opening 25 at the same distance from the center as is the orifice 23. This may best be done by puncturing a hole in the material immediately beneath the orifice when the spout is in pouring position. 85 When said spout is turned so that said orifice and opening are in registration, the position 26 indicated in dotted lines in Fig. 1 will be assumed and the contents of the can may be discharged. By a quarter turn the 90 position indicated by the reference numeral 27 will be assumed and the opening in the closure will be effectively closed. It is thus apparent that my invention serves both as a temporary closure during the time when 95 the contents of the can are being consumed, and as a discharging spout as previously stated.

The method of attachment heretofore described renders possible an indefinite use of 100 the spout, as it may be removed from an emptied can and attached to a full one of the same type. It is, therefore, not essential that the spout be provided with each container, and it may be independently 105 furnished if desired.

It is thought that the invention and many of its attendant advantages will be understood from the foregoing description, and it will be apparent that various changes 110

may be made in the form, construction and arrangement of the parts without departing from the spirit and scope of the invention or sacrificing all of its material advantages, the form hereinbefore described being merely a preferred embodiment thereof.

I claim:

1. In a container, the combination of an end formed with a hole and an outstanding neck around said hole, a closure having an opening and otherwise closing said hole and formed with seam flanges embracing said neck, the inner flange of said closure tapering outwardly, and a pouring spout having a base which tapers outwardly and is seated in said closure so as to be rotatably confined therein by the tapered flange thereof, the base of the spout having an eccentrically located orifice adapted to be registered with or cut off from the opening of the closure by the turning of the spout.

2. In a container, the combination of an end formed with a hole, a closure having an

opening and secured to said end over said hole, said closure having an outwardly tapering peripheral flange, and a spout formed with a base which tapers outwardly and is seated in said closure so as to be rotatably confined therein by the tapered flange thereof, the base of the spout having an eccentrically located orifice adapted to be registered with or cut off from the opening of the closure by the turning of the spout.

3. A container comprising a body of any usual or preferred construction, a closure for a filling hole in an end thereof, and a removable pouring spout having an upstanding wall, an extended lip, and an upwardly tapered plug portion adapted to be snapped into a correspondingly tapered depression in said closure and being rotatable therein, said plug portion having an eccentric orifice adapted to be turned into and out of registration with an opening provided in said closure.

JOHN M. HOTHERSALL.
